(No Model.)

L. SEPULCHRE.

LAMP FOR BURNING PETROLEUM AND LIGHT OILS.

No. 356,507.

Patented Jan. 25, 1887.

UNITED STATES PATENT OFFICE.

LOUIS SEPULCHRE, OF LIEGE, BELGIUM.

LAMP FOR BURNING PETROLEUM AND LIGHT OILS.

SPECIFICATION forming part of Letters Patent No. 356,507, dated January 25, 1887.

Application filed December 26, 1885. Serial No. 186,607. (No model.) Patented in Belgium January 31, 1885, No. 67,717; in France February 7, 1885, No. 166,879; in England February 11, 1885, No. 1,916, May 14, 1885, No. 5,952, and July 11, 1885, No. 8,401; in Austria-Hungary July 22, 1885, No. 17,801 and No. 38,596; in Victoria November 19, 1885, No. 4,318; in Queensland November 26, 1885, No. 86; in New South Wales January 12, 1886, No. 1,756; in Italy January 15, 1886, No. 340; in New Zealand February 16, 1886, No. 1,716; in India March 19, 1886, No. 637; in Canada May 21, 1886, No. 24,115, and in Spain September 25, 1886.

To all whom it may concern:

Be it known that I, LOUIS SEPULCHRE, a subject of the King of the Belgians, residing at Liege, in the Province of Liege and Kingdom of Belgium, have invented certain new and useful Improvements in Lamps for Burning Petroleum and Light Oils, parts of which are also applicable to gas-burners, (for which I have obtained protection in Great Britain, No. 1,916, dated February 11, 1885, No. 5,952, dated May 14, 1885, and No. 8,401, July 11, 1885; Letters Patent in Belgium, No. 67,717, dated January 31, 1885; in France, No. 166,879, dated February 7, 1885; in Austria-Hungary, No. 17,801 and No. 38,596, July 22, 1885; India, specification filed March 19, 1886, Register 49 of 1886, No. 637; Canada, No. 24,115, dated May 21, 1886; Victoria, No. 4,318, dated November 19, 1885; New South Wales, No. 1,756, Book 2, dated January 12, 1886; Queensland, Register of Patents No. 86, page 18, dated November 26, 1885; New Zealand, No. 1,716, dated February 16, 1886; Italy, No. 340, dated January 15, 1886; claimed September 25, 1886, in Spain,) of which the following is a specification.

My invention relates to certain improvements applied to lamps in which a central current of air is supplied to the burner; and it consists in the general construction, combination, and arrangement of parts, as herein-after described, and illustrated in the accompanying drawings, in which—

Figure 1 is a sectional elevation of a lamp embodying my improvements; Fig. 2, a sectional plan of the same through the wick-tubes; Fig. 3, a similar view to Fig. 1, but illustrating a modification of the air duct and chamber; Fig. 4, a sectional plan of the same. Fig. 5 is a sectional view through the cap and air-diffuser detached. Fig. 6 is a similar view, but with the flange of the cap bent at an acute angle. Figs. 7 to 9 illustrate the application of my improved air-chamber to suit two or more flat wicks and of varying forms; and Figs. 10 to 13 represent various forms of my air-chamber and disk adapted to round or cylindrical wicks.

A indicates the reservoir; B, inner wick-tube; C, guide for same; D, central air-duct; 50 d, wings for supporting same; E, disk or button; F, air-chamber; f, perforations in same; G, cap for wick; g, flange or projection formed upon upper end of cap G; H, winding mechanism for wick; I, cover for protecting same; 55 K, support for chimney; L, gallery for globe.

In Figs. 1 and 2 it will be seen that I take a part of the central current of air by means of a tube, D, suited to the size of the burner and fitted in the center thereof. By this tube 60 D, the part F of which is perforated laterally and closed at its upper end, I bring the special current of air up to a convenient height and distribute it, heated to a high temperature, by the holes f, perforated laterally, to all points 65 of the flame; or I take the air intended for the chamber F from perforations made in the disk E, in this case the tube D serving as support, and the air-duct is replaced by a solid support. 70

F is essentially a special chamber of suitable shape, open toward the bottom to receive a part of the central current of the burner, closed at its upper end, and perforated laterally, whatever may be the shape—rounded, straight, or 75 tapered—of the upper closed surface of the same.

In burners having two or three flat wicks I obtain the desired result, as shown, Figs. 7, 8, and 9, by means of a cap slit above the 80 wicks, which, by the solid part preserved between the flames and by the particular shape of this solid part, divides and projects the central current of air upon the burning gases. I place upon the cap G, between the flames, 85 an air-chamber, F, receiving part of the central current of air and distributing it heated by the holes f to every part of the flames.

In Figs. 10, 11, 12, and 13 I show several arrangements in combination with a button, E. 90 This button E is soldered on the tube D at the base of the air-chamber F, and is intended to spread or divert toward the gases in combustion the part of the central current of air not taken for the aforesaid air-chamber. This button E may be of a flat shape; but I prefer and 95

claim as novel the shape concave toward the bottom—conical or rounded—as being superior to the old shape, in that this concave button E bends the current back toward the burning gases more powerfully and at a sharper angle than the flat shape, and that there is obtained thereby a sufficient enlargement or spreading of the flame with a button E of less diameter.

10 I may use the ordinary cap with rounded or conical top in combination with my air chamber or diffuser F and concave button E; but the form of cap shown on the drawings will more forcibly divert the outer current of air 15 upon the gases in combustion, and I propose to use this cap G with flange g at right angle, as in Fig. 5, or at acute angle, as in Fig. 6, in combination with my air-chamber F and my concave-disk button E.

20 Having fully described my invention, what I desire to claim and secure by Letters Patent is—

1. In a central-draft lamp, the combination, with suitable reservoir and draft and wick tubes, of a laterally-perforated air conveying and heating chamber provided with a flange or disk secured to the exterior thereof below the air-heating perforations, the said air heat-

ing and conveying device being located above the top of the draft and wick tubes, as set forth. 30

2. In a central-draft lamp, the combination, with suitable reservoir and draft and wick tubes, of a laterally-perforated air conveying and heating chamber provided with a concave disk secured to the exterior thereof below the 35 perforations through which the heated air passes to the flame, the said air heating and conveying device being located above the top of the draft and wick tubes, substantially as shown and described.

3. In a central-draft lamp, the combination, with suitable reservoir, draft and wick tubes, and the imperforate flanged cap G, of a laterally-perforated air conveying and heating chamber located above and connected with the 40 draft-tube, and provided with the concave button E, permanently fixed below the air-heating perforations of said chamber, substantially as shown and described.

In testimony whereof I have hereunto set my 50 hand in presence of two witnesses.

LOUIS SEPULCHRE.

Witnesses:

PIERRE BISSOT,
JOSEPH GERARD.
